UNITED STATES PATENT OFFICE.

E. B. BANKER, OF SCHAGHTICOKE, NEW YORK.

RAILROAD-CHAIR.

Specification of Letters Patent No. 31,071, dated January 8, 1861.

To all whom it may concern:

Be it known that I, E. B. BANKER, of Schaghticoke, in the county of Rensselaer and State of New York, have invented a new and useful Improvement in Railroad-Chairs; and I do hereby declare that the following is a full, clear, and exact description thereof, reference being had to the accompanying drawings, making a part of this specification, in which—

Figure 1, is a top view of the improved chair holding the ends of two sections of rail-road rail. Fig. 2, is a bottom view of Fig. 1. Fig. 3, is an inside end view of one half of the improved chair with a rail secured to it. Fig. 4, is an inside end view of the opposite half of the same.

Similar letters of reference indicate corresponding parts in the several figures.

This invention is a new and improved chair for connecting the ends of rail-road rails, and for securing said rails at the joints, in a rigid and permanent manner on the cross ties.

My invention consists of two double-lapped half chairs united by a double-lapped joint, formed as will be hereinafter described in combination with a transverse wedge which forces the lips of the rail base up against the jaws of the chair, and at the same time rigidly binds together the two halves of the chair, all as will be hereinafter described.

To enable those skilled in the art to make and use my invention, I will proceed to describe its construction and operation.

My invention is fully illustrated in the accompanying drawings, in which A, A', are two oblong rectangular portions which form the bed pieces of the chair, B, B, are curved jaws projecting up from the top of bed piece A, and B', B', are similar jaws which project up from the top surface of bed piece A'. These four jaws are all of the same shape and their inner surfaces are formed so as to correspond with the upper surfaces of the lower lips of the rail-road rail and to fit snugly against the neck or web of the rail, as represented in Figs. 3 and 4 of the drawings, wherein the jaws of the chair are shown grasping the base portion of the rail C.

The base pieces A, A', are somewhat wider (in a direction with the length of the rail C,) than their respective jaws B, and B', as shown in Fig. 1, thus leaving on one side of

the jaws of each base piece a portion a, a, projecting, the surfaces of which portions a, a, are inclined from a plane parallel with the plane of the rail base, or seats, between the jaws B, B, and B', B', on which the ends 60 of the rail sections rest.

On one side of a central line drawn longitudinally through the base piece A, and projecting a suitable distance from the inside end a, of this piece, is a lip b, the edges of 65 which are perpendicular to the plane of the rail base, and the top surface of this lip b, is in a plane with the surface a, a, of the base piece A. The vertical central edge of this lip b, abuts against the corresponding 70 edge of a similar lip b', which projects from the inside end a, a, of the base piece A', and the vertical transverse edges, or ends of the lips b, and b', abut against the corresponding vertical ends a, a, of the base pieces A, 75 A'. When these lips b, and b', are thus brought together each lip overlaps and rests on a corresponding lower lip, i. e., the lip b, of base piece A, rests upon a corresponding lip b², of base piece A', and the lip b', of 80 base piece A, rests on a corresponding lip b³, of base piece A'. The vertical longitudinal edges of these lower lips b², and b³, abut in the same manner as described for the upper lips b, and b'. These lips prevent the chain 85 (at its joint) from being moved out of its place laterally, when it is properly spiked down on the cross tie, and at the same time they form a solid bed or base for a wedge which is used to lock all the parts together 90 in securing the rail ends to the chair.

The portions G, G', which project out longitudinally from the outside ends of the base pieces A, A', and whose upper surfaces are in the plane of the rail seats, form bridges 95 for giving additional support to the rail base beyond the ends of the base pieces A, A', of the chair.

The ends of the rail sections C, meet in the center of the space between the jaws B, B, 100 and B', B', as shown in Fig. 1, where they are secured by a transverse wedge J, shown in Figs. 1, and 3, which is driven into the space between the inclined surface of the projecting portions a, a, of the base pieces A, A', and the horizontal plane surface of the rail base. This wedge J when driven hard into this space presses both ends of the rail up against the jaws of the chair and at the same time draws the horizontal surfaces 105 110

of the lips b , b' , b^2 , b^3 , together and locks the ends of the rails down rigidly to the chair; and the wedge, when in this position, forms a seat for the ends of the rails at the 5 joint.

Four hold-down spikes are used with this compound chair, two to each section, to secure the chair to the cross tie, and when thus secured the ends of the rails will be prevented from moving either laterally or vertically. 10

I do not claim broadly the use of a transverse wedge for locking up the rail ends, but

What I do claim as new and desire to secure by Letters Patent, is;

The combination of wedge J, with the divided or compound chair, the same consisting of the jaws B, B, and B', B', extended base pieces A, A', with their inclined surfaces, and the lapping and abutting lips b , b' , b^2 , b^3 , all arranged in the manner specified. 15 20

E. B. BANKER.
